UNITED STATES PATENT OFFICE.

WILLIAM C. AUSTIN, OF ANDERSON, SOUTH CAROLINA.

PIPE-FORMING MACHINE.

Application filed April 24, 1925. Serial No. 25,646.

To all whom it may concern:

Be it known that I, WILLIAM C. AUSTIN, a citizen of the United States, residing at Anderson, in the county of Anderson and 5 State of South Carolina, have invented certain new and useful Improvements in Pipe-Forming Machines, of which the following is a specification.

My invention relates to a machine for 10 forming pipes with bell ends, which may be used as sewer pipes, or for other purposes, and which are formed of concrete, or other plastic material.

An important object of the invention is to 15 provide means for suitably packing or condensing the bell end of the pipe, without employing two movable or rotary formers, whereby a simplified machine is produced.

A further object of the invention is to 20 prove the construction of the rotary former, which produces the body portion of the pipe, for obtaining, first a rolling or kneading action upon the plastic material and subsequently a smoothing action.

25 A further object of the invention is to provide means to lock the pallet within the bell end of the mold, whereby it is removed from the machine with the mold, upon the completion of the pipe.

30 A further object of the invention is to provide the pallet with groove cutting means, whereby grooves may be formed upon the interior of the bell end of the pipe, which operation occurs after the pipe is completed, and removed from the machine.

35 A further object of the invention is to provide a machine of the character described, which is of simplified construction, strong and durable.

40 Other objects and advantages of the invention will be apparent during the course of the following description.

In the accompanying drawings forming a 45 part of this specification and in which like numerals are employed to designate like parts throughout the same,

Figure 1 is a side elevation of a pipe forming machine embodying my invention,

Figure 2 is an end elevation of the same,

50 Figure 3 is a horizontal section taken on line 3—3 of Figure 1,

Figure 4 is a horizontal section taken on line 4—4 of Figure 7,

Figure 5 is a similar view taken on line

5—5 of Figure 7, with the cam levers folded, 55 and looking downwardly,

Figure 6 is a similar view taken on line 5—5 of Figure 7, with the cam levers opened, and looking upwardly,

Figure 7 is a central vertical sectional 60 view through the mold, and associated elements, parts broken away, and parts in elevation, and,

Figure 8 is a fragmentary vertical section 65 through the lower end of the mold and associated elements.

The machine embodies a frame work, including base beams 10, such as I-beams, upon which upwardly converging standards 11 are rigidly secured. These standards are 70 rigidly connected at their tops by transverse beams 12, and also by longitudinal beams 13.

Disposed upon the forward end of the beams 10 is a floor 14, rigidly attached thereto, by any suitable means. This floor supports a table 15. This table is held stationary upon the floor by any suitable means. The table embodies a raised cylindrical portion 16, having a flat horizontal top 17. The table also carries a marginal flange 18. The 80 table 15 is provided upon its periphery, and adjacent to its top with an annular groove 19, affording a flat horizontal face 20, and an inclined face or wall 21. Beneath the flat horizontal face 20, the table has an annular groove 22, for the reception of spring bolts, to be described.

The numeral 23 designates a mold, provided at its bottom with a bell end 24. This mold is preferably formed in two parts, 90 which are detachably secured together by any suitable means. For the purpose of illustration I have shown the mold sections provided with apertured ears 25, connected by bolts 26 while any other suitable means 95 may be employed for this purpose. The mold 23 is vertically arranged in use, and its bell end is provided at its bottom with a reinforcing guide flange 27. This guide flange is adapted to slidably receive the 100 raised cylindrical portion 16 of the table. When the mold 23 is in the raised position, prior to the packing or condensing of the bell end of the pipe, the guide flange 27 fits or slidably engages about the flange of a 105 pallet, to be described. The flange 27 is adapted to rest upon and be supported by yielding means, embodying a ring 28, rest-

ing upon and attached to suitably stiff compressible coil springs 29, the lower ends of which are held within sockets 30, formed upon the horizontal flange 18 of the table. 5 The springs 29 are adapted to support the mold in this elevated position, but the mold may be shifted longitudinally or depressed, in opposition to these springs, as will be described. It is obvious that other forms of 10 yielding means may be employed to support the mold to permit of its longitudinal shifting or packing action. The mold is provided upon its inner surface, adjacent to its upper end, with ribs 31, which are adapted to form 15 grooves upon the exterior of the small end of the pipe.

Adapted to be arranged upon the upper end of the mold 23 is a ring or holding member 32, having a depending annular flange 33, receiving the upper end of the mold. The concrete or other plastic material is fed through the ring 32 into the upper end of the mold, by any suitable means. The holding member or ring 32 is provided at diametrically opposite points with blocks 34, rigidly secured thereto, and these blocks are adapted to engage beneath compression cams 35, pivoted between vertical arms or brackets 36, attached to a horizontal transverse beam 37, in turn attached to the front standards 17. The cams 35, which are eccentrically pivoted, are adapted to be turned upon these pivots by means of a bail 38. It might be stated at this point, that after the 30 mold 23 is positioned in place upon the table, the cams may be turned downwardly slightly, whereby the mold is securely held in the raised position. Further downwardly turning movement of the cams will effect a further downward movement of the mold, as is obvious. The holding member or ring 32 is provided at diametrically disposed points with apertured radially extending ears 39, receiving vertical rods 40, which are adapted to slide vertically through stationary guides 41 and 41', carried by the frame.

Arranged upon the cylindrical raised portion 16 of the table is a tapered or frustoconical pallet 42, decreasing in diameter upwardly. This pallet is provided at its top with an inwardly projecting horizontal annular flange 43, and at its bottom with an outwardly projecting annular flange 44. The flange 44 is adapted for insertion within the groove 19, to be held therein. The periphery of the flange 44 does not project beyond the periphery of the cylindrical raised portion 16 of the table, and this flange is adapted to pass into the bell end 24 of the mold. The pallet is stationary in operation, upon the machine, nor does it function to support the mold, which must be free to move longitudinally with relation thereto.

The pallet 42 is provided upon its periphery, see more particularly Figures 4, 5,

and 6, with circumferentially extending horizontal pairs of slots 45, for receiving curved groove cutters 46, which are preferably resilient and attached at corresponding ends to the pallet, as shown at 47. These groove cutters are provided at their free end with inwardly projecting heads 48, adapted for engagement with cam heads 49, carried by cam levers 50. These cam levers are pivoted to knuckles 51, rigidly attached to the interior of the pallet, as shown. The levers 50 are adapted to be folded or shifted to a corresponding position, to be out of the way of the rotary former, to be described. When the levers 50 are swung outwardly, as shown in Figure 6, they shift the groove cutters 46 outwardly, and the cam heads 49 contact with the interior of the pallet, thus limiting the further movement of the levers in the same direction. When swung to the outer positions, these levers may be employed to turn the pallet whereby the groove cutters will produce the grooves upon the interior of the bell end of the pipe. It should be stated that the pallet remains stationary during its presence upon the machine, but when the pipe has been completed upon the machine, the mold 23 is removed from the machine and placed upon a suitable support, at which time the pallet is turned by means of the levers to produce the grooves as described.

The bell end 24 of the mold carries spring bolts 52, attached thereto at 53, and these spring bolts have heads 53', projecting radially inwardly through openings 54 in the bell end and into the annular groove 22 in the elevated portion of the table. The inner ends of these heads 53 are beveled, as shown at 55. It is therefore seen that when the mold 30 is depressed to the lowermost position, that the heads 53' will ride over the flange 44 of the pallet, and then spring inwardly and engage beneath it, thereby holding or locking the pallet in the bell end of the mold, so that it cannot move downwardly out of the same. These bolts may be equipped with handles 57, by means of which they may be moved outwardly, to release the pallet, after the mold is removed from the machine, and it is desired to remove the pallet from the same.

The machine further embodies a rotary former 58, including a cylindrical smoothing drum 59, which is rigidly mounted upon a vertical drive shaft 60. This drive shaft is slidably mounted within a bearing 61, rigidly attached to the beam 37 and within a bearing 62, rigidly attached to the beam 12. The drum 59 has its head 63 provided with pivot elements or bolts 64, passing through openings therein, and through openings in a cross head 65, also preferably rigidly mounted upon the drive shaft 60. Disposed between the head 63 and cross head

- 65 are rotary rollers 66, pivoted upon the elements 64. These rollers have their peripheries preferably substantially flush with the periphery of the smoothing drum 59.
- 5 While the former is bodily rotating the rollers 66 rotate upon their axes, and exert a rolling or kneading action upon the concrete or other plastic material. As the smoothing drum follows these rollers, it 10 will exert a smoothing action upon the concrete previously treated by the rollers. The former is preferably provided with a filler 66', arranged between the parts 63 and 65, and attached thereto.
- 15 The drive shaft 60 is rotated by means of a pulley 67, mounted upon the upper end of the drive shaft, and splined thereon, so that it will rotate the shaft, but will permit of the longitudinal movement of the 20 shaft. The pulley is held against vertical displacement by the bearings 62 and 62', as shown. The pulley is driven by a belt 67', engaging a pulley 68, carried by a transverse shaft 69, journaled in bearings 70, which are attached to the upper beams 13. This belt passes downwardly and engages a pulley 71, rigidly mounted upon a shaft 72, journaled in a bearing 73. The shaft 72 is driven by a motor 74 or other source 25 of power.
- The drive shaft 60 and the rotary former carried thereby will be lowered by gravity, and the same may be raised by a cross head 75, having a hub 76, slidably receiving the 30 shaft 60. A collar 77 is clamped to the shaft 60 by a bolt 78 or the like, and is disposed above the hub 76, to engage therewith. The cross head 75 has connection with cables 79, passed about grooved pulleys 80, 35 secured to the upper portion of the frame and about grooved pulleys 81, secured to the beams 13. These cables are attached to and wound upon drums 82, which are rigidly mounted upon the transverse shaft 83, 40 journaled in stationary bearings 84. One drum 82 is equipped with a beveled gear 85, rigidly attached thereto, and this beveled gear engages a beveled gear 86, carried by the shaft 87, journaled in a bearing 88.
- 45 The shaft 87 is disposed in end to end relation to the shaft 72, and is adapted to be connected therewith by means of a friction clutch 89, which may be thrown out of action by a suitable lever 90. It is preferred 50 to drive the winding drums by power but they may be manually operated, if desired.
- The cross head 75 is adapted to engage with stops 91, which may be clamped upon the vertical rods 40, at selected elevations.
- 55 When the cross head engages beneath the stops 91, the rods 40 will carry the holding ring 32 upwardly, causing the same to disengage the mold. The purpose of providing the friction clutch 89 is to prevent 60 breakage of parts of the machine, should the rods 40 be shifted to the uppermost position, while the shaft 87 is still being driven.
- The operation of the machine is as follows:
- The mold 23 is placed in position with its bell end resting upon the yielding means, embodying the ring 28 and springs 29, and such bell end receives the flange 44 of the pallet and the upper end of the elevated cylindrical portion 16 of the table. The 70 mold may be retained in this elevated position by swinging the cams 35 downwardly slightly. The rotary former 58 is now in the lowermost position and the smoothing drum embodied therein is disposed within 75 the pallet. This former may be rotating. The concrete is now poured into the upper end of the mold 23, through the holding ring 32 and will of course pass into the bell end 24 of the mold. When sufficient concrete 80 has been fed into the mold to fill the bell end of the mold and form the bell end of the pipe, the mold 23 is depressed, which is accomplished by swinging the bail 38 downwardly, to turn the cams 35 downwardly. 85 This bail may be manually moved, or automatically shifted by a movable part of the machine. The mold is therefore given a compressing or packing operation or movement. This movement may consist of a continuous downward movement, or a number of reciprocatory movements. The mold 23 is finally moved downwardly to the lowermost position, which will occur when the 90 heads 53' of the bolts engage beneath the flange 44 of the pallet. In this manner the concrete between the bell end of the mold and the pallet will be condensed or compressed. Further concrete is now poured into the mold, and the former 58 is continuously rotated, while it is gradually elevated, 95 for forming the body of the pipe. While the former is bodily rotating, the rollers 66 turn freely upon their axes, and they produce a rolling or kneading action upon the concrete, which is followed by the smoothing action of the rotating smoothing drum 59. When the pipe is completed, the bail 38 is shifted upwardly so that its cams release the holding ring 32, and subsequently 100 to this, the continuous rise of the cross head 75, brings the same into contact with the stops 91, whereby the rods 40 are elevated in turn elevating the holding ring and effecting a disengagement between it and the top 105 of the mold. The pallet 42 being locked within the bell end of the mold 23, is removed from the machine with the mold, so that the mold and pallet may be positioned upon the table of the machine to form another pipe. This removed mold with the 110 finished pipe is suitably supported, and the levers 50 swung outwardly, Figure 6, and may be employed to rotate the pallet with 115 in the bell end of the pipe, causing the ex- 120 125 130

panded groove cutters 46 to form the grooves upon the inner surfaces of the bell end of the pipe. After this, the levers 50 are swung inwardly and the groove cutters automatically retract so that the pallet may be moved from or within the bell end of the pipe. The mold 23 is of course separated into halves and removed from the pipe, which is allowed to set and harden.

10 It is to be understood that the form of my invention herewith shown and described is to be taken as a preferred example of the same, and that various changes in the shape, size, and arrangement of parts may be resorted to without departing from the spirit of my invention or scope of the subjoined claims.

Having thus described my invention, I claim:

20 1. In a pipe forming machine, a mold having a bell end, a pallet held stationary in the bell end, means for effecting a packing operation of the mold with relation to the pallet, and a former operating within the mold to complete the body of the pipe.

25 2. In a pipe forming machine, a mold having a bell end, a pallet held stationary in the bell end, means for effecting a longitudinal movement of the mold with respect to the pallet, and a former for operation in the mold to complete the body of the pipe.

30 3. In a pipe forming machine, a mold having a bell end, a pallet arranged near the bell end, means to move the mold longitudinally toward the pallet, and a former for operation in the mold to complete the body of the pipe.

35 4. In a pipe forming machine, a mold having a bell end, a pallet within the bell end, means for effecting a longitudinal movement of the mold, a rotary former for operation within the mold, and means to move the former longitudinally of the mold.

40 5. In a pipe forming machine, a mold having a bell end, a relatively stationary pallet adapted for receiving the bell end about the same, yielding means for supporting the mold, means for moving the mold longitudinally in opposition to the yielding means, a rotary former for operation within the mold, and means to move the rotary former away from the pallet.

45 6. In a pipe forming machine, a support, a pallet held relatively stationary by the support, an upstanding mold mounted upon the support and arranged above the pallet and having a bell end, means to depress the mold, a rotary former for operation within the mold, and means to move the rotary former upwardly away from the pallet.

50 7. In a pipe forming machine, a support, a pallet upon the support, an upstanding mold having a bell end, supporting means between the mold and support and adapted to permit of the downward movement of the

50 mold, a holding ring engaging the upper end of the mold, means to engage the holding ring and to depress the same and hold the same depressed, a rotary former to operate within the mold, and means automatically operated upon the upward movement of the former to elevate the holding ring.

8. In a pipe forming machine, a support, yielding means arranged near the support, a mold having a bell end supported by the yielding means, means for depressing the mold, a pallet carried by the support to co-operate with said bell end, and a rotary former for operation within the mold to produce the body portion of the pipe.

9. In a pipe forming machine, a longitudinally movable mold having a bell end, a pallet adapted to enter said bell end, means for holding the pallet relatively stationary, means for supporting the mold in place so that it may move longitudinally toward the relatively stationary pallet, and a former operating within the mold for producing the body portion of the pipe.

10. In a pipe forming machine, an elevated table portion, a pallet mounted upon the elevated table portion, a mold having a bell end adapted to be moved downwardly about the elevated table portion, means for effecting the longitudinal movement of the mold, means to lock the pallet to the mold, and a former operating within the mold to produce the body portion of the pipe.

11. In a pipe forming machine, a table, a pallet mounted upon the table, said pallet and table having interfitting parts, said pallet having a radially extending flange, a mold having a bell end which is adapted to receive the flange of the pallet, means for supporting the mold and to effect its longitudinal movement, catch means carried by the mold to engage beneath the flange of the pallet when said mold is shifted longitudinally in one direction sufficiently, and a rotary former operating within the mold to produce the body portion of the pipe.

12. In a pipe forming machine, an elevated table portion provided with a circumferential groove, an annular pallet provided near its lower end with a radial flange to be seated within said groove, a mold having a bell end to receive the pallet and elevated table portion, spring catches carried by the mold and adapted to be automatically engaged beneath the flange of the pallet, means for supporting the mold and effecting its downward movement, and a rotary former operating within the mold to produce the body portion of the pipe, said former having a part thereof adapted to telescope with the annular pallet.

13. In a pipe forming machine, a pallet held stationary in use, a longitudinally movable mold having a bell end receiving all parts of the pallet within its bore, the bell

end of the mold co-acting with the stationary pallet to condense the bell end of the pipe being formed upon the longitudinal movement of said mold, and a rotary former 5 within the mold for producing the body portion of the pipe, said rotary former having a part to telescope with the pallet.

14. In a pipe forming machine, a mold having a bell end, means for holding the 10 mold in position, a member within the bell end for co-action therewith, and a rotary former to operate within the mold to produce the body portion of the pipe, said rotary former embodying a trailing smoothing drum and rollers disposed in advance of the drum, said rollers rotating bodily 15 with the drum and also turning on their axes with relation to the drum.

15. A rotary former for a pipe making 20 machine, comprising a rotatable smoothing drum, and rollers arranged in advance of the drum and connected therewith, said rollers rotating bodily with the drum and also turning upon their axes with respect to the 25 drum.

16. A rotary former for a pipe making machine, comprising a rotatable smoothing drum, rollers connected with the leading 30 end of the drum and adapted to bodily rotate therewith and turn with relation thereto, said rollers having their peripheries substantially flush with the periphery of the smoothing drum.

17. A rotary former for a pipe making 35 machine, comprising a former head, rollers connected with the former head to bodily rotate therewith and turn upon their axes with relation thereto, and a smoothing drum connected with the former head to rotate 40 bodily therewith.

18. In a pipe forming machine, a mold having a bell end, a pallet to be received 45 within said bell end, groove forming means carried by the pallet to produce grooves upon the interior of the bell end of the pipe, approximately oppositely arranged handles to project the groove forming means and also serving to remove the pallet, and a former operating within the mold to produce the 50 body portion of the pipe.

19. In a pipe forming machine, a mold having a bell end, a pallet held within such bell end, groove forming means carried by the pallet, foldable means to operate the groove forming means, and a rotary former 55 to operate within the mold, said rotary former including a portion telescoping within said pallet, said foldable means permitting such telescoping action.

20. In a pipe forming machine, a mold 60 having a bell end, a member supported within the bell end and having a groove or grooves, an outwardly movable groove cutting element or elements carried by the member and operating within the groove or 65 grooves, means to shift the groove cutting element or elements outwardly, and a rotary former operating within the mold, said rotary former embodying a smoothing drum and rollers connected therewith, said rollers 70 rotating bodily with the drum and turning upon their axes with relation thereto.

21. In a pipe forming machine, a mold having a bell end, a pallet to enter the bell 75 end, nonrotatable means carrying and supporting the pallet, means for effecting a relative longitudinal movement between the mold and the pallet for condensing the material in the bell end, and a former operating within the mold to complete the body 80 of the pipe.

22. In a pipe forming machine, a mold having a bell end, a nonrotating pallet within the bell end, means for effecting a relative longitudinal movement between the 85 mold and the pallet for condensing the material in the bell end, and a former for operation in the mold to complete the body of the pipe.

23. In a pipe forming machine, a mold 90 having a bell end, a nonrotating pallet within the bell end, means for effecting a relative longitudinal movement between the mold and pallet, means for locking the pallet to the mold upon such relatively longitudinal movement, and a former for operation in the mold to complete the body of the pipe.

In testimony whereof I affix my signature.

WILLIAM C. AUSTIN.
